HIS ATTORNEYS

UNITED STATES PATENT OFFICE

JAMES J. O'SHEA, OF DALLAS, TEXAS

LAUNDRY MACHINE

Application filed February 4, 1930. Serial No. 425,846.

This invention relates to improvements in laundry appliances, and particularly to a neckband or collar former adapted to set or position the shirt on the working surface of an ironing table.

Primarily, the object of the invention is to provide a neckband or collar former of a shirt setting device for ironing tables that is capable of being contracted to a minimum size and expanded to a maximum size.

A further object is to simplify the construction and mode of operation of the device, the parts thereof being reduced considerably in number, while at the same time, the rigidity of the working parts remains unimpaired. These objects are preferably accomplished by the provision of a former constituted of two arms slidable toward and from each other in a frame in one direction and a former section mounted in said frame to slide or move in a direction preferably at right angles to the direction of movement of the arms. In this structure, the former section is separate and spaced from the arms so that the former is readily distinguishable from the expandible ring device usually employed for the shaping of shirt neckbands. In simplifying the construction and arrangement of the working parts, the operating lever which is provided for contracting the former also constitutes a portion of the connections between the former section and the arms of the former so as to impart movement to said arms upon actuation of the former section.

With these and other objects in view, the invention consists in certain details of construction and combinations and arrangements of parts, all as will hereinafter be more fully described and the novel feature thereof particularly pointed out in the appended claims.

In the accompanying drawings:

Figure 1 is a side-elevation of an ironing table with a shirt placed thereon and the

neckband former mounted on the working surface of the table, the former being shown in neckband engaging position and expanded, in dotted lines;

Fig. 2 is a vertical sectional view of the former and frame on which it is mounted;

Fig. 3 is a sectional view on the line 3—3 of Fig. 1, taken in the direction indicated by the arrows;

Fig. 4 is a detail plan view, partly in section, and some of the parts broken away, showing the former expanded;

Fig. 5 is a detail sectional view on the line 5—5 of Fig. 2, taken in the direction indicated by the arrows; and

Fig. 6 is a detail perspective view of the latch for the operating lever.

In the accompanying drawings, an ironing table is indicated at 10, and attached thereto is the base portion 11 of a standard 12. Standard 12 has a vertically extending slot 13 therein, and working in this slot is a pair of bolts 14 secured in a frame which is preferably of U-shape cross section, so as to provide depending legs 15, 15a. Mounted within a housing 16 on the top of the frame is a bolt 17 urged outwardly of the housing by a spring 18, so as to engage over the upper end of standard 12 when the frame is raised to its elevated position, as shown in Figure 1. The frame is thus releasably held in this elevated position but can be lowered by retracting said bolt 17, a projection 19 on said bolt and extending through housing 16 being provided for this purpose.

In order that the former for imparting shape to the neckband or collar of the shirt may be contracted to a minimum size and expanded to a maximum size, it is preferably formed of two laterally extensible members, 20 and a third section that is movable away from said members in a direction preferably at right angles to the direction in which said members are adapted to be expanded. Preferably, there is a pair of arms 20, 20a slidably

mounted in a guideway 21 on the leg 15 of the frame, whereby said arms 20, 20a may be moved toward and from one another or expanded, so to speak, laterally of the frame. In advance of these arms, there is what is termed a former section 22 adapted to be moved away from the frame or at right angles to the direction in which the arms 20, 20a are movable. Preferably, this former section 22 is provided with one or more extensions 23 in the form of L-shaped rods, one end of each rod being attached to the former, while the other end of each rod is slidably received in a sleeve 24 located between the legs 15, 15a of the frame. Interposed between the frame and a pin 25 extending transversely of each extension or rod 23 is a coil spring 26 that normally tends to urge the former section 22 away from the frame and the arms 20, 20a.

To expand the former, it is necessary that arms 20, 20a be moved away from one another at the same time that the former section 22 is moved away from said arms. Accordingly, there is a vertically disposed operating lever 27 pivoted at 28 on a bracket 28a on leg 15 of the frame, and the lower end of this lever is connected to former 22 by link 29. Pivotedly connected to lever 27 by pivot pin 30 and pivotally and slidably connected to a bracket 31 on leg 15 by a pin and slot connection 32, is a vertically disposed link 33, whose lower end is connected by a pin and slot connection (see Fig. 5) with a pair of links 34, 34a which, in turn, are connected to the arms 20, 20a, respectively. This pin and slot connection between said links consists in having the lower end of link 33 offset as at 35, said offset portion having a slot 36 therein, in which is slidably received the pin 37, this pin extending through the links 34, 34a, being held therein by cotter pin 38 so as to connect said links together. With this arrangement, when former section 22 is moved away from the frame, operating lever 27 is rocked on its pivotal center 28 and link 33 is rocked on pin 32, so as to move the lower end of link 33 to leg 15 of the frame, this movement of the lower end of the link 33, causing the ends of links 34, 34a attached to arms 20, 20a to spread apart or move away from one another and imparting a similar spreading or expanding action to said arms. The parts are shown in this expanded position in Figs. 2 and 4 and in dotted lines in Figure 1. It might be added that the former is not permitted to assume this expanded position until after it has been inserted or positioned in the neckband or collar of a shirt on the ironing table. That is, the former is normally contracted and locked in its elevated position, as shown in full lines in Figure 1, and is not lowered and expanded as shown in dotted lines in said Figure 1 until a shirt has been placed on the board in posi-

tion to have the former positioned within the neckband or collar thereof.

It is, of course, necessary, or rather advantageous, to have means for retaining the former contracted until the operator chooses to permit it to expand. For this reason, the operating lever 27 is adapted to engage in a recess in bracket 31 when the arms and former section are moved to their contracted positions. The recess in bracket 31 may be formed by an offset or projection 39 on said bracket, as shown in Fig. 6. This form of connections between the operating lever and former and the arms 20, 20a, simplifies the mechanism for expanding and contracting those elements, in that the operating lever constitutes a part of the connections between the former and the arms.

In addition to this simplification of the operating connections and the unusual extent to which the former may be expanded or contracted, the present device is quite advantageous by reason of the fact that the operator need only disengage bolt 17 from standard 13, lower the former into the neckband or collar of the shirt, and release operating lever 27 from projection or latch 39. The former will then automatically expand to the limit allowed by the neckband or collar and firmly hold the said shirt on the table 10, the operator having free use of both hands for straightening the shirt, as thus held preparatory to actually ironing or finishing the laundering of the shirt.

What I claim is:

1. In a shirt setting device for ironing tables, a frame, a former composed of a pair of arms, said arms being slidable toward and from each other in said frame, a section movable in a direction toward and from the line of movement of said arms, means for yieldingly moving said former section away from said arms, and connections between said section and said arms operable to move the arms away from each other.

2. In a shirt setting device for ironing tables, a neckband former comprising a pair of arms movable bodily toward and from each other and a section movable toward and from said arms but spaced therefrom, a spring for yieldingly moving said former section away from said arms, an operating lever for moving said section toward said arms, and connections between said lever and arms for moving said arms away from each other when said section is moved away from the arms and for moving said arms toward each other when said section is moved toward the arms.

3. In a shirt setting device for ironing tables, a frame, a collar former consisting of a pair of arms slidable away from each other in said frame and a former section, and means for simultaneously moving said section away from said arms and said arms away from

each other, said means comprising an operating lever and connections between said lever and said arms and section by which said arms are moved toward each other and said section is moved toward said arms.

5. 4. In a shirt setting device for ironing tables, a frame, a collar former composed of a pair of arms slidable to and from each other in said frame and a former section, a spring 10 for moving said section away from said arms, and a vertically disposed operating lever pivoted on said frame and connections between said lever and said section and arms whereby said arms will be moved away from each other 15 by said spring when said section is moved away from said arms and whereby said arms may be moved toward each other and the section moved toward said arms.

5. 20. In a shirt setting device for ironing tables, a frame, a collar former composed of a pair of arms slidable in the frame, and a former section movable toward and from said arms, an operating lever pivoted on said frame, a link pivotally attached to said lever 25 and frame and connected to said arms whereby said arms may be moved toward each other, one of said pivotal attachments being loose, an operating connection between said lever and former section whereby said section 30 may be moved toward the line of movement of said arms, and a spring means for yieldingly moving said former section away from said arms and said arms away from each other.

35. 6. In a shirt setting device for ironing tables, a frame, a collar former composed of a pair of arms slidably mounted in said frame and a section spaced from said arms and having an extension slidable in said frame at 40 right angles to the direction of movement of said arms, means for yieldingly moving said arms away from each other and said section away from said arms, an operating lever and operating connections from said lever to said 45 arms and section for moving said arms toward each other and the section toward said arms.

7. 5. In a shirt setting device for ironing tables, a frame, a collar former composed of a 50 section and a pair of arms each slidably supported in said frame, said section being movable at an angle to the direction of movement of the arms, an operating lever pivoted on said frame and attached to said section, a link 55 pivotally attached to said frame and lever, one of said pivotal attachments being loose, a link attached to each arm, a pin connecting said last mentioned links and loosely engaging said other link, whereby said arms may 60 be moved toward each other and said section moved toward said arms by said operating lever, and a spring for imparting reverse movements to said arms and former section.

8. 65. In a shirt setting device for ironing tables, a frame having a pair of guides there-

in, a pair of rods slidable in said guides, a neckband former section mounted on said rods, means for yieldingly urging said rods and former section away from said frame, a pair of arms, said arms and section constituting a former, said arms being movable 70 away from each other in a direction at an angle to the direction of movement of said former section, and means for moving said arms toward each other and the former section toward said frame. 75
